UNITED STATES PATENT OFFICE.

RICHARD A. HUDDNUT, OF NEW YORK, N. Y.

DESIGN FOR A KEY-HANDLE.

42,942.

Specification for Design.

Patented Aug. 27, 1912.

Application filed February 3, 1912. Serial No. 675,395. Term of patent 14 years.

To all whom it may concern:

Be it known that I, RICHARD A. HUDDNUT, a citizen of the United States, and a resident of the city, county, and State of New York, have invented a new, original, and ornamental Design for Key-Handles, of which the following is a specification, reference being had to the accompanying drawing, forming a part hereof.

The figure is a perspective elevation of a key handle embodying my new design.

I claim:

The ornamental design for a key handle, as shown.

RICHARD A. HUDDNUT.

Witnesses:

EDWIN Ross,
WM. F. PURNELL.
